UNITED STATES PATENT OFFICE.

CHARLES JOHN GLASEL, OF COLOGNE, GERMANY.

HIDE-TREATING MACHINE.

1,034,783.

Specification of Letters Patent. Patented Aug. 6, 1912.

Application filed February 5, 1909. Serial No. 478,209.

To all whom it may concern:

Be it known that I, CHARLES J. GLASEL, citizen of the United States, residing at Cologne, in the Kingdom of Prussia and Empire of Germany, have invented certain new and useful Improvements in Hide-Treating Machines, of which the following is a specification.

The present invention relates to machinery for treating hides or skins.

The object of the invention is an improvement in the method of treating hides by the production of improved mechanism for depilating, excarnifying, stretching, smoothing, brushing, and generally the working of hides or skins in the art of tanning.

By the utilization of my improved machinery the hide is simultaneously worked or acted upon in a plurality of directions, thus evenly flattening, extending or stretching and smoothing the skin, regularly, and consequently distributing or enlarging the area or surface, and also producing a more regular product. The hide may be similarly worked upon either the pelt side or the grain side, with the accompanying use of tools, preferably rollers, especially adapted for the purpose.

With these objects in view the invention, mechanically considered consists essentially of a tool carrying head sections of which are capable of vertical, transverse oscillating, longitudinal, and a transversely zigzag motion; novel features of construction and combinations of arrangements of parts whereby the sections of the tool are caused to travel on diverging or converging lines; or in directions toward and away from each other; reversing means for this purpose; means for holding the hide in position while being worked, and certain other improved features.

In the accompanying drawings I have illustrated one example of the physical embodiment of exemplification of my invention, constructed according to the best mode I have so far devised for the practical application of the principle, and certain modified tools, adapted for different purposes in the treatment of hides.

Referring to these drawings: Figure 1 is a front view of the machine tool head and a sectional tool, together with actuating parts, some elements of the embodiment being

omitted. Fig. 2 is a side view of Fig. 1, 55 some parts being omitted and others added. Fig. 3 is a view of the machine in Fig. 1. the tools (rollers) in a different position from Fig. 1. Figs. 4, 5, and 6 show different tools, used for different purposes, and 60 all adapted for use on the tool head. Fig. 7 is an enlarged view in side elevation, illustrating the tool provided with presser roll for holding the hide in position, means being illustrated for reversing the rotary 65 movement of the roll coincident with the reversal of movement of the tool. And Fig. 8 is a front view of Fig. 7. Fig. 9 illustrates means for rotating the shaft 5 of the tool head. Fig. 10 illustrates means for reversing the rotation of spindle 7. Fig. 11 illustrates means for actuating the plunger 39.

The tool-head as a whole is indicated by the numeral 1, the platform 2 of which is 75 provided with flanged ribs 3, 3, which are adapted to slide longitudinally on the base of the I-beams 4, 4, this motion being produced by the screw 5, turning in the threaded nut 6 on the platform 2. As shown in Fig. 5 the screw 5 may be turned through the medium of the gear 5^a on screw 5, and gear 5^b from the drive wheel 5^c on shaft 5^d. The rotation of the screw 5 in the nut 6 causes the tool head 1 to advance, and a 85 reverse movement of the screw causes the reverse movement of the head.

A spindle 7 provided with right and left hand screws, is suspended from the platform by means of the hangers 8, 8 and is provided with a set of pulleys 9, 10, 11 journaled thereon. The spindle 7 may be reversed in its rotation by means of the pulleys 10 and 11, over which open and crossed belts may be passed for driving the pulleys to rotate 95 the spindle in alternate directions. Directly below the spindle, the shaft 12 is supported by stationary hangers 13, 13 from the platform. This shaft has journaled thereon a pair of pulleys 14, one of which is adapted 100 to receive motion from the pulleys 10 or 11 to impart rotary motion to said shaft. A spline 15 extends throughout practically the length of the shaft and upon this spline a pair of tools or hide rollers 16, 16 is keyed, 105 the hubs of the respective rollers being formed with a pair of collars 17, between which the forked ends or legs 18 of the

guide arms 19, 19, are located. These guide arms are formed at their upper ends as nuts 20, one threaded to receive the right hand and the other the left hand screw of the 5 spindle 7. The extreme upper end of these arms are mortised at 21 and are adapted to slide along on the rib or tenon 22 on the under surface of the platform 2. From this construction it is evident that as power 10 is applied to the pulley 10 of the series of pulleys to rotate the spindle 7, the shaft 12 is also rotated. The rotation of the spindle and shaft imparts rotation to the rollers, and the action of the oppositely threaded 15 screws on the spindle causes the guide arms 19 to travel toward and away from each other, suitable mechanism being provided for the reversal of motion of the spindle. The arms are guided in their lateral movement 20 by the mortises 21 sliding along the rib or tenon 22, and as the entire tool-head moves forward and is reversed in its longitudinal movement by the screw 5, the lateral movement of the forked arms carrying 25 with them the rollers, causes the rollers to travel in alternating relatively diverging and converging lines over the surface of the hide. Preferably the hide 23 is supported on a flat table capable of rotation on a vertical axis, or it may be supported on a rotary support, as a cylinder or an endless revolving support, none of these elements being shown however. In addition to the travel of the rollers on the above indicated 30 lines, they may be propelled either in parallel lines, or converging and diverging lines, with a zigzag movement. This action is attained by means of the sleeve 25 journaled on the spindle 7. This sleeve is provided 35 with a pair of grooves, as the annulus 26 and the continuous cam groove 27. A movable pin 28 is adapted to engage either of these grooves. When engaging the groove 27, it will be evident that the action of the 40 cam as it rotates, will be to impart a reciprocating movement to the spindle 7, thus causing the rollers to travel in a zigzag manner. With the pin engaging the circular slot, the spindle is held laterally stationary. 45

During the operation of the tool head, the hide is liable to be displaced by the motion of the rollers, and in order to prevent this undesired movement I employ a pressing 55 roller 30 which is supported in a flexible and yielding manner. The roller 30 is supported from the shaft 12 by bracket 31 and is pressed down upon the hide by means of the angle levers 32, 33 which are pivoted at 60 34 and 35, and whose action will be understood, especially on references to Figs. 2 and 7. As a reversal of rotation of this pressing roller is required with each longitudinal reversal of the motion of the tool head, I provide a 65 system of levers, 36, 37, 38 operated by a

plunger 39, to actuate the pawls or dogs 40 one at each end of the roller, adapted to engage a rack wheel 41, and thus stop the motion of the roller. The plunger may be reciprocated by suitable mechanism not shown, adapting it to coöperate with lever 36 as shown. Obviously the pressing roller is thus permitted to revolve only in direction corresponding to the changes of direction of the movement of the tool head. A second pressing roller could be used if desired. 70

As shown in Fig. 2 the vertical movement of the tool head may be adjusted by means of a rack wheel *a* which engages rack teeth *b* on the angular arm *c* which is pivoted on the rod *d*, at the rear of the head. A journal bar *e* also pivoted on rod *d* supports the shaft 12 and this bar and angular arm *c* are connected by spring *f*. By turning the wheel *a*, the tension of the springs *f* may be increased or decreased as desired, thus increasing or diminishing the flexibility of the tool head. 80

Having thus fully described my invention what I claim as new and desire to secure by Letters Patent is: 85

1. The combination with a reciprocating tool head, a rolling tool, and means for imparting motion to said tool in zigzag lines with relation to the movement of the head. 90

2. The combination with a reciprocating tool-head of a sectional rolling tool, and means for imparting motion to said sections in zigzag lines. 95

3. The combination with a reciprocating tool head, a sectional rolling tool, means for operating said sections in alternately converging and diverging lines, and means for imparting motion to said tool in zigzag lines with relation to the movement of the head. 100

4. The combination with a movable tool head and its sectional rotating tool, of means for imparting longitudinal movement to the tool head, and means for moving the sections of the tool laterally in their rotary movement, toward and away from each other. 105

5. The combination with a longitudinally reciprocating tool head and a sectional rotary tool, of means for laterally moving the sections of the tool toward and away from each other, and means for imparting a zigzag motion to sections. 110

6. A tool head, a pair of rolling tools carried thereby, and means for bodily moving said tools toward and away from each other, alternately, as the tools pass over the surface of a hide. 115

7. A reciprocating tool head, a sectional rolling tool carried thereby, flexibly supported, means for operating said sections in alternately converging and diverging lines, and means for imparting motion to said tool in zigzag lines with relation to the movement of the head. 120

8. A reciprocating tool head, a sectional 125

rolling tool carried thereby, flexibly supported, and means for operating said sections in alternately converging and diverging lines.

movement to the tool with relation to the movement of the head.
